EMILE BRONNERT, OF MULHAUSEN, ALSACE-LORRAINE, FRANCE.

PROCESS OF DRYING ARTIFICIAL SILK.

Application filed September 3, 1920. Serial No. 408,037.

To all whom it may concern:

Be it known that I, EMILE BRONNERT, a citizen of the Republic of France, residing at 1 Quai du Barrage, Mulhausen, Alsace-Lorraine, France, have invented certain new and useful Improvements in Processes of Drying Artificial Silk, of which the following is a specification.

This invention relates to a rapid drying process for freshly precipitated cellulose hydrate threads.

As is well known, there exists a very great difference in the time necessary for drying a freshly precipitated more or less gelatinous thread of cellulose hydrate and that necessary for the same thread, which, after the first drying process, is again saturated with water and dried under the otherwise usual conditions. The first-named sort of gelatinous threads especially must be preserved from being weakened or from taking a brownish color, due to decomposition of the hydrate of cellulose.

The difference in the time necessary for drying is due to the fact that water diffuses much more rapidly from artificial silk thread which has once been fixed by drying than from the colloidal and gelatinous thread freshly precipitated or even from the thread which is approaching the normal solid state upon progressive drying. Differences of permeability of the material in a different physical state, and different strength of capillary forces may be the reasons of this phenomenon.

The insufficient attention given to these considerations has given rise to the very uneconomical and tedious arrangements hitherto used for drying fresh gelatinous threads of cellulose hydrates. These threads are mostly wound upon rollers or spools of glass, metal or other acid-proof, water-proof and heat-resisting material in relatively thin layers and piled up in ventilated and warmed rooms. It has already been proposed to make this storage or stacking up in different chambers and to use over again the air that has been cooled by the evaporation of water in one chamber, by re-heating it up to the temperature normally used. The counter-current principle has also been employed, but the drying process lasted for days, the temperature scarcely exceeding 60 to 70° C., so that this plan was not economical.

The reluctance to adopt other means is

undoubtedly to be attributed to the fact that the soft thread quickly changed color and became brown when the temperature was raised higher than 60 to 70° C., like a damp white cotton fabric brought into contact with too hot an iron. Upon dyeing these damaged threads with suitable dyes (for example methylene blue) it was demonstrable that a chemical change had taken place at the said points. This change happened especially on the outer layer of the threads on the spool, when the latter had stood too near to the radiator. From this it was deduced that the soft texture of the threads could not stand any high temperature, while according to present-day observation the fault was undoubtedly due to differences in the temperature of the heated air in the same cross section of the apparatus, that is, to a want of perfect thermal equilibrium of the air in the said section.

It was the large production, in recent times, of such threads as the so-called staple fibres, wool substitute, and the like, which once again compelled attention to be given, on the basis of fundamentally new considerations, to the search for a better drying process.

Hence this invention consists in the process, for drying cellulose hydrate filaments, by employing temperatures higher than have hitherto been held to be applicable, without impairing them. This is accomplished by using a strong current of air, care being taken by proper measures that the contact of the air with the threads is as intimate as possible and that at any given time, in any cross section of the apparatus, the temperature is perfectly uniform. The threads may if preferred be wound on rollers in the known manner indicated above, but the invention is in no way limited to the drying of threads so wound.

In the event of the drying operation proceeding by steps, the air coming from one step or chamber has to be heated up again to the higher temperature and thoroughly mixed before being blown again upon the threads.

Of course the highest admissible temperature given to the current of air cannot be maintained throughout all the apparatus, but exists only at the entrance to each new step, when the air coming from the step before has been heated up again and reaches the threads. In each subsequent cross sec-

tion of chamber transverse to the flow of air the temperature is lowered as long as there is moisture to be evaporated, but the strong current of air and the measures taken for thorough mixing and intimate contact have to ensure that the temperatures are perfectly uniform to each cross section, though varying from one cross-section to another.

A high temperature of course ensures quick and very economical drying, as hot air takes up and carries away incomparably more water than cooler air. This economy was to be expected on theoretical grounds; but for a long time no one thought of employing a higher temperature in practice, as in experiments an impairing of the dried material was always observed.

In the accompanying drawings various forms of drying apparatus are illustrated in which my process may be practiced.

Figure 1 is a diagrammatic longitudinal section of such apparatus.

Figs. 2, 3 and 4 are similar views of other forms of such apparatus.

According to Fig. 1, the drying passage is provided with vertical walls c_1 which are perforated to allow air to pass and which form the drying chambers a_1 wherein the material to be dried is placed. Between each pair of walls c_1 a space is left for the reception of heating coils b_1 . The perforated walls c_1 may consist of lattice work or of perforated plates. The air flows in the direction of the arrows through the various chambers. The air which has been cooled in the first chamber by drying the material deposited therein, is, upon passing out of the chamber into the next chamber not only quite uniformly heated by the heating coil b_1 , but also, in consequence of the numerous uniformly distributed openings in the walls c_1 is thoroughly mixed, so that only air which has been uniformly heated in all parts and is therefore in thermal equilibrium is admitted to the material deposited in the chamber next in line. The same procedure is followed in the subsequent chambers formed by the spaced walls separating them.

In the construction of the apparatus illustrated in Fig. 2, the tops and the bottoms of the drying chambers a_2 are formed of perforated walls c_2 and the heating coils b_2 are accommodated in between spaced impervious walls between the chambers a_2 and which separate the drying chambers from one another. In the case of this arrangement also, the current of air, in passing through the horizontal perforated walls c_2 is so mixed that it enters the drying chambers in a uniformly heated condition.

While in the apparatus according to Fig. 2, the air in all the drying chambers flows from above downwards, in that according to Fig. 3, the air in the drying chambers will

flow alternately downwards and upwards. In this form of apparatus the heating coils b_3 are housed in special communication passages which are arranged at the top of the apparatus. The air flowing downwards out of one chamber a_3 passes through the perforated walls c_3 at the bottom into the next chamber through the upper perforated wall and the aperture i_3 into the heating passage, is here heated up again and then flows through the aperture l_3 and the upper perforated wall of the drying chamber into the latter chamber and so forth. Hence in this case the re-heating of the air only takes place once for every other chamber.

In Fig. 4 similar heating passages are also arranged at the bottom of the apparatus, so that the air will be pre-heated before entering every chamber, as will at once be obvious.

Arrangements may be made if desired for removing the material which is first dried without waiting until all the fibres in all the chambers are ready for removal, or for shifting the material from one chamber to another in any well known manner, or disconnecting the chambers singly from the hot-air circuit. Such arrangements however form no part of the invention, as the threads exposed to the hottest and driest air may quite safely be left there until the drying is completed throughout.

The dimensions of the chambers, and the number of times the same air may advantageously be reheated, will naturally vary according to circumstances and will be determined by calculation or experience. Probably from four to eight chambers might be conveniently used and in any case the number is not likely to be much greater than ten. On the other hand it will be borne in mind that the process according to the invention may be carried out in a single chamber without any second heating of the air.

Trials made with air which has been heated to a temperature of from 100° to 130° or even 140° C. showed that it was quite possible to dry, under the conditions prescribed, at this higher and therefore more economical temperature. The means of realizing these conditions are generally known and are not claimed in conjunction with this invention. It will be understood that gases other than air which do not affect cellulose may be employed in this process, and when I speak of air in the claims such other gases are included.

What I claim is:

1. The step in the process of producing artificial silk which comprises subjecting gelatinous cellulose hydrate to the action of a continuously moving current of hot air, of a temperature of 100° C. to 140° C.
2. The step in the process of producing

artificial silk which comprises subjecting freshly precipitated more or less gelatinous cellulose hydrate to the action of a continuously moving strong current of hot air, of a temperature of 100° C. to 140° C., the said current of air being brought into intimate contact with the threads and its temperature at any given time being substantially the same at all parts of any given 10 cross section of the drying chamber taken transversely to the direction of flow of the current of air.

In witness whereof, I have hereunto signed my name in the presence of two subscribing witnesses.

EMILE BRONNERT.
